UNITED STATES PATENT OFFICE.

CHARLES P. MADSEN, OF CHICAGO, ILLINOIS, ASSIGNOR, BY MESNE ASSIGNMENTS, TO PELOUZE MANUFACTURING COMPANY, OF CHICAGO, ILLINOIS, A CORPORATION OF ILLINOIS.

ELECTRIC SWITCH FOR SAD-IRONS.

1,036,868.

Specification of Letters Patent. Patented Aug. 27, 1912.

Original application filed January 22, 1908, Serial No. 412,176. Divided and this application filed February 11, 1911. Serial No. 608,051.

To all whom it may concern:

Be it known that I, CHARLES P. MADSEN, a citizen of the United States, and a resident of Chicago, Cook county, Illinois, have invented a certain new, useful, and Improved Electric Switch for Sad-Irons, of which the following is a full, true, clear, and exact description, such as will enable others skilled in the art to which it appertains to make 10 and use the same.

My invention relates to electrically heated articles and has particular reference to means for controlling the electric current to electric sad irons.

15 A serious objection to the usual electrically heated sad irons lies in the fact that the current supply to the iron cannot be regulated or controlled. In consequence the proper ironing temperature cannot be maintained, and the iron becomes abnormally heated if left in the circuit too long and thereby scorches the clothes.

20 One of the objects of my invention is to provide means for controlling the electric current supply to the iron at the will of the operator and while the iron is in use so that the temperature of the iron may be properly regulated to suit ironing conditions.

From another standpoint an object of my 25 invention is to provide a separable plug for the iron which may be readily connected to or disconnected from the iron but which will be so related to the iron and particularly to the handle thereof as to constitute a controlling switch operable by a hand gripping the handle during the ironing process for shutting off or turning on the current as described.

Another and more particular object of my 30 invention is to provide an electrically heated sad iron and a heater therefor, in combination with an attachment or terminal plug co-acting with the terminals of the electric heater to form a combined controlling 35 switch and plug, together with means for holding the plug in its proper position while it is serving its dual function.

Other objects of my invention will appear hereinafter.

40 I will describe one of the numerous embodiments of my invention in the accompanying drawings, wherein:

Figure 1 is a longitudinal vertical section of a sad iron showing the correlation of the

iron and the means for controlling the current; Fig. 2 is a transverse vertical sectional view on line 2—2 of Fig. 1; Fig. 3 is a top plan view of the iron shown in the preceding figures, the handle being removed so as not to interfere with the view of the parts beneath the handle, this view being taken on the section line 3—3 of Fig. 1; Fig. 4 is an enlarged longitudinal sectional view of the switch and plug member; and Fig. 5 is a bottom plan view of the combined switch 55 and plug, part thereof being shown in section.

The sad iron which is shown in the drawings and which I have chosen as best illustrative of my invention, is of the type shown 70 in my co-pending applications, Serial No. 412,176, filed January 22, 1908, and No. 454,355 filed September 23, 1908, wherein the subject matter of this application is disclosed; this being a divisional application 75 primarily of my said application Serial No. 412,176.

The sad iron comprises in general four principal elements, namely: The hot plate A, which is provided with a polished bottom for smoothing and ironing purposes; the heater element or unit B, by means of which the heat is supplied to the hot plate; the top or weight member C, which furnishes the desired weight to the iron; and 80 the handle D. The hot plate preferably consists of a flat, thin rimless metal plate, of substantially triangular shape, and constitutes the bottom element of the iron. This plate has a central upstanding enlargement A', preferably of triangular form, which is adapted to interlock with a correspondingly shaped opening in the heater element so as to prevent relative rotation of the heater element and hot plate. In this 85 construction of sad iron, the heater element B is preferably made as a separate article of manufacture, and is made conveniently removable as a unit so that it may be replaced by a new heater at comparatively small cost in the event the heater 90 should become damaged. It consists of a plate of refractory insulating material B' having a triangular central opening B'' which receives and interlocks with the upstanding enlargement on the hot plate. On 95 its under surface or face this insulating plate has a broad, shallow, flat-bottomed

recess B''' wherein is preferably embedded a single plane heating conductor 1. This heating conductor lies close to the hot plate, as shown in Fig. 1, so that practically all of 5 the heat is transmitted directly to the hot plate, very little, if any, being dissipated in the upper portion of the iron body. The conductor is electrically insulated from the hot plate, however, by means of a sheet of 10 mica 2 or other suitable insulating material.

In order to further carry out the unitary idea of the heating element, the ends of the winding are connected, as shown in Fig. 2, to parallel upstanding contact blades or 15 strips 3 suitably secured to the insulating plate. These blades are stiffened and held in their proper position by means of a column of insulating material fastened to the plate and projecting upwardly through a 20 tapered opening 5 in the top element or weight portion of the iron.

The heater unit constitutes the intermediate element of the sad iron and is interposed, as will be seen in Figs. 1 and 2, between the hot plate and the upper member, 25 the three portions or elements of the iron being preferably clamped together by means of a single fastening or clamping device. This consists of a bolt 6 upstanding from 30 the central enlargement of the hot plate, and a nut 7 screwed on the upper end thereof for clamping the elements together, the bolt passing through an enlarged hole 8 in the member C.

35 A very desirable feature in electrically heated sad irons is to maintain the upper portion thereof as cool as possible, and to confine the heat to the bottom or ironing surface. In order to carry out this idea, 40 I prefer to provide the weight element or member C with a large comparatively deep cavity C' in its underside, and to fill this cavity with a loosely packed heat insulating material such as asbestos and magnesia. In 45 addition to this, I interpose an insulating washer 9 between the nut and the member C, as shown in Fig. 1, so as to prevent the heat from the upstanding post or bolt 6 from reaching the member C. It will be 50 seen that this construction provides a rather thin flange, so to speak, at the lower edge of the member C which reduces the actual contact between said member and the heater to a comparatively small area. This flange 55 co-acts with a shouldered edge B''' of the insulating plate and constitutes a peripheral interlockment therebetween which prevents any relative rotation.

It will be noted that the insulating 60 washer, the nut and the end of the bolt all lie within a rather deep recess or depression 10 in the member C, the purpose of this being to keep these parts well within the body of the iron and at the same time have 65 as little iron as possible immediately sur-

rounding the bolt so that the heat will not be absorbed thereby. The handle member D, by which the iron is manipulated, comprises a gripping portion D' located above the body of the iron and substantially parallel thereto. The grip D' is mounted upon a suitably formed post D'' securely fastened to the front end of the member C by means of a bolt D'''.

70 It will be noted that the handle is fastened to the front end of the iron only, the purpose of this being that it leaves a clear space between the rear portion of the handle and the body of the iron for the connecting leads and for the proper manipulation of the switch, as hereinafter described. The handle also performs another function: It operates with the lugs C''' projecting from the rear end of the iron to form a rest for the iron when it is tipped up on end.

75 As before intimated, the contact blades 3, which are carried by the heater unit, project upwardly beyond the insulating column 4 and into a rectangular recess or groove 12. This channel or recess extends 80 from the depression 10 to the rear end of the iron and forms a guide for the movable switch plug S. In some instances I make the switch permanent on the iron in position to be operated from the handle D, and 85 I provide a separate plug for connecting the conductor leads to the iron, but, speaking generally, the most acceptable arrangement is the combined switch and plug, this being 90 preferably reciprocatory or movable in the channel guide 12 so as to engage or disengage the contact blades or heater terminals 3 which project into the channel 12. It being 95 essential that the block be held in the channel subject to its reciprocating movement, and at the same time be capable of being completely removed when desired to entirely disconnect the iron, I have provided a spring member which yieldingly presses upon the 100 upper side of the block. One end 13 of this 105 spring is provided with an enlarged hole through which the bolt 6 passes, and is firmly clamped under the insulating washer 9. It has an intermediate portion 13' which rises upward at the end of the guide channel 12. From the upper end of the portion 13' is a portion 13'' lying substantially parallel and above the switch block S. This 110 portion of the spring is bifurcated or forked so as to provide a slot for the reception of 115 the knob of the switch block and in addition it serves as a limit stop for the switch. The free ends of the bifurcations are bent 120 to form catches 13''' which snap into shallow grooves 14 in the upper face of the 125 block. The grooves 14 correspond to the position wherein the switch plug is disconnected from the heater contact blades. When the switch is moved into engagement with the contact blades the bent ends 130

of the spring snap over the rear of the block and yieldingly hold the block in such position. It will be noted that, although the switch plug is partially locked in either 5 of its operative positions, it may at any time be easily removed from the iron by simply pulling it out of its channel endwise.

Attention is particularly directed to the 10 fact that the switch block is disposed in a position beneath the handle of the iron. My reason in so positioning the switch is to make it possible for convenient operation in its channel by the person's hand while 15 gripping the handle during the use of the iron. It is only necessary that one or two of the fingers of the hand grip the little knob S', provided for the purpose, in order to shift the switch into or out of connection 20 with the heater terminals, this being accomplished without removing the hand from the handle. Thus it will be seen that during the process of ironing, should the iron become too hot it is simply necessary to 25 shift the switch to its disconnected position, thereby permitting the iron to cool down to the desired temperature without interrupting the ironing process.

It will be clearly understood that any desirable 30 form of switching device may be used. When the combined plug and switch, which I have shown, is employed it may be made to move laterally or vertically as desired. I find that the form of combined switch and plug, shown in the drawings, seems to be most acceptable to users of the iron. It comprises a rectangular block 35 of suitable insulating material of a size to slidily fit the guide channel 12. The block contains longitudinal holes or bores 40 16 and slots 17, each of the latter opening through the bottom of the block so that the slots and holes form recesses to receive the upper ends of respective contact blades 3. On the sides of the block are lateral holes 18 45 which communicate with the respective longitudinal holes. Each longitudinal hole contains a contact member which forms a terminal for the conductor leads F. The terminals are adapted to engage the contact 50 blades 3. Each of the contact members comprises a straight leaf portion 19 having an outwardly turned beveled end, and a bent or leaf spring 20 the free end of which is oppositely turned. The two leaves of each contact member or terminal are suitably fastened together and contain a threaded hole for a binding screw 21. The binding screws extend into the lateral holes 18 so that they 55 may be reached by a screw driver or tool when it is desired to connect the cord thereto. These lateral holes are sufficiently larger than the binding screws to permit considerable movement of the terminal members. 60 It will be seen that thus constructed, the

terminals form flexible or floating jaws and my purpose in arranging them in this manner is to permit them to have free movement within certain limits so that they may readily adapt themselves to any irregularities in construction. Furthermore, should the contact blades or terminals become slightly bent by accident the operation of the switch will not be interfered with. The 70 flexible conductors F are brought together 75 to the rear end of the block through a rubber protector or sleeve F' and the ends of the conductor pass through holes 22 in the block and thence to their respective terminal members to which they are fastened by 80 means of the binding screws 21. The purpose of the rubber sleeve is to protect the conductors and to prevent an accidental shock to the user. In addition to this, I 85 provide a flexible metal spring anchored to the block by the screw 23, for the purpose of holding the leads vertical for a portion of their length immediately above the block so that when the iron is tipped up on end the conductors will not be bent or broken. 90

It will readily be seen that my invention may assume various shapes and be embodied in different structures without departing from the spirit of the invention. I desire my invention to be construed accordingly. 95

I claim:

1. An electric sad iron, comprising a sad iron body, a handle for said body, and an electric heater located in the body, in combination with a movable switch for said 100 heater mounted on the body to be operated by a hand gripping handle a clip for holding the switch in open and closed positions, and holding means for the clip.

2. In an electric sad iron, the combination 105 with an electrically heated sad iron body and terminals therefor, a handle for the body, and a combined electric switch and plug slidably but detachably mounted on the body and having a handle portion located under the handle of the body, to be engaged by the fingers of the user's hand gripping the handle for sliding said switch plug into and out of engagement with said terminals. 110

3. An electric sad iron, the combination 115 with an electrically heated sad iron body, a handle therefor, and an electric heater located in the body, terminals therefor, in combination with a movable electric switch located on the top of the body independent of but adjacent to the handle in position to be manually moved between fixed points for connection and disconnection with the heater terminals. 120

4. An electric sad iron, comprising a body, and a heating winding mounted in the body and having protruding terminals, an operating handle mounted on the body and extending rearwardly thereabove, a slidible switch 130

mounted on the top of the body to engage the said terminals, a device secured to the body and adapted to yieldingly hold said switch in open or closed position with respect to said terminals, and operating means on the switch disposed beneath the handle within reach of the fingers of the hand gripping the handle.

5. An electric sad iron, comprising a body, a handle connected therewith, and a heating device mounted therein and having terminals projecting from the body, a switch slidably mounted on the body and including circuit terminals arranged to engage and disengage said terminals, a stop device secured to the body adapted to yieldingly bear on the switch and hold the latter in open or closed circuit position, and a projecting member on the switch arranged 15 within reach of the fingers of the operator's hand when gripping the handle.

6. In an electric sad iron, the combination with a sad iron body having an upstanding handle, of an electric heater therein having terminals projecting from the body, and a combined switch and plug comprising a casing slidable upon said body in position to be operated without removing the hand from said handle, and a conductor attached to 20 said casing and having terminal fingers that are movable into and out of engagement with the terminals upon the movement of the casing.

7. A switch block for sad irons, comprising a substantially rectangular body of insulating material containing parallel holes, parallel slots and lateral openings, in combination with self-adapting contact jaws in said holes, binding screws in respective lateral openings, and jaws and electrical conductors in respective holes and connected with respective jaws by respective binding screws.

8. A switch block for sad irons comprising a substantially rectangular body of insulating material containing parallel holes, parallel slots and lateral openings, in combination with a self-adapting contact jaw loosely placed in each said hole, binding screws in respective lateral openings, and electrical conductors loosely placed in respective holes and connected with respective jaws by respective binding screws.

9. A switch block for sad irons, comprising a knobbed block or body of insulating material containing contact slots and cavities, in combination with floating contacts in said cavities, arranged to automatically adjust themselves to the contacts with which 55 they engage, conductors connected with said contacts, within said cavities, suitably insu-

lated and joined outside said block, and a resilient holder therefor on said block, substantially as described.

10. The improvements herein described comprising an electrically heated sad-iron having terminal contacts connected to its heating means, in combination with a terminal plug connected to the current supply leads and adapted to be removably mounted upon said iron in engagement with said terminals to complete the circuit to the iron, and means permitting said terminal plug to be shifted on said iron to open the circuit without detaching said plug from the iron. 65

11. The improvements herein described comprising an electrically heated sad-iron having terminal contacts connected to its heating means, in combination with a terminal plug connected to the current supply leads and adapted to be removably mounted upon said iron in engagement with said terminals to complete the circuit to the iron, means permitting said plug to be bodily shifted on said iron to open the circuit without detaching said plug from the iron, and a handle for said iron arranged in position to enable the user's hand to operate said plug on said iron without removing the hand from the handle. 80

12. The improvements herein described comprising an electrically heated sad-iron having terminal contacts connected to its heating means, in combination with a terminal plug connected to the current supply leads and adapted to be detachably mounted upon said iron in engagement with said terminals to complete the circuit to the iron, a holding device permitting said plug to be shifted through a limited range on said iron 90 to open the circuit without detaching said plug from the iron, and an upstanding operating handle mounted on the forward end of said iron so as not to interfere with the free manipulation of said plug and the attached current supply. 100

13. In an electric sad iron, comprising a base plate, a shell, and a handle secured to the top of the shell, an electric heating element contained in the shell, a pair of lead wires for said heating element entering the shell, and a switch mounted on the shell directly under the handle, and adapted for controlling the connection between the heating element and the lead wires. 110

In testimony whereof, I have hereunto set my hand this 4th day of February, 1911, in the presence of two subscribing witnesses.

CHARLES P. MADSEN.
